UNITED STATES PATENT OFFICE.

FRANK P. MILLER, OF DOWNTON, PENNSYLVANIA.

PAPER-MAKING MACHINE.

1,362,499.

Specification of Letters Patent. Patented Dec. 14, 1920.

Application filed December 13, 1918. Serial No. 266,640.

To all whom it may concern:

Be it known that I, FRANK P. MILLER, a citizen of the United States, and a resident of Downingtown, county of Chester, State of Pennsylvania, have invented certain Improvements in Paper-Making Machines, of which the following is a specification.

One object of my invention is to improve the construction and arrangement of machines for the manufacture of paper, so that the ground area occupied by the building in which the machine is located will be materially reduced.

A further object of the invention is to design the machine that the drying cylinders will be located on a separate floor from the making mechanism and the calendering rolls and cutters.

A still further object of the invention is to provide means whereby the moisture, arising from the wet paper being dried by means of the calendering rolls, will not condense and drop onto the paper being formed or upon the finished paper.

A further object of the invention is to so design the machine that longitudinal air currents will be avoided and that the moist heated air will pass direct to ventilation at the roof of the building, and that fresh air will be supplied from the lower floor.

These objects I attain in the following manner, reference being had to the accompanying drawings, in which:—

Figure 1, is a longitudinal sectional view 35 through a factory building, showing the paper making machine, calendering rolls, and the cutting machines on the lower floor, and the drying machines on the upper floor above the first mentioned machines;

Fig. 2, is a plan view of the machines on the first floor, showing the paper making and calendering rolls and the cutting machines;

Fig. 3, is a plan view of the upper floor, 45 showing the drying cylinders; and

Fig. 4, is a transverse sectional view through the building on the line 4—4, Fig. 1.

In the manufacture of paper and particularly paper known as "box board," which 50 is comparatively heavy and consists of a number of plies, the paper, or stock, is of low grade. The demand now calls for large quantities, which must be made on extremely large machines having a great width and 55 of such a length that the paper can be made continuously and received in a dry condi-

tion at the cutters to be cut into the required sheets. Ordinarily, a machine for accomplishing this purpose is of great length and occupies considerable floor space. The 60 drying cylinders are located at the center of the building and the making mechanism is at one end, and the calendering rolls and cutters are at the other end, consequently the moisture rising from the drying paper 65 on the drying cylinders travels toward each end of the building and condenses, dropping on the paper being made and on the finished paper.

I have found that I can save about fifty 70 per cent. in the length of a building and can protect the paper while it is being formed, as well as the finished paper, from the moisture from the drying cylinders, and can carry off the moisture from said cylinders 75 as soon as it is formed by the arrangement I will now proceed to describe.

Referring to the drawings, 1 is the building in which the machinery is located. 2 is the ground floor. 3 is the floor of the second 80 story and 4 is the roof which, in the present instance is shown flat but it may be of any form desired. The second floor is discontinued at each end to allow for the passage of the paper to and from the drying apparatus on said floor.

5 is a series of paper making machines of the cylinder type, in the present instance, each having a vat 6 and a making screen cylinder 7. The paper from the making 90 mechanism passes to a series of press rolls 8, then to the guide rolls 9, and to the first series of drying rolls 10, which are vertically arranged, in the present instance, on a standard 11 at one end of the building; the standard 95 and extending through the space in the floor 3.

Mounted on the floor 3 of the second story of the building is the drying mechanism 12 consisting of a frame on which are mounted 100 the drying cylinders 13 and 14. The cylinders 14 are located above the spaces between the cylinders 13 and the paper passes around these cylinders in the manner shown in Fig. 1. These cylinders are of a number 105 sufficient to dry the paper before it leaves the machine at the opposite end of the building, where it passes down and around the final cylinders 21 and then around the two sets of calendering rolls 22 and 23, in 110 the present instance, which give a finish to the paper and press it to the proper degree,

The paper then passes to the cutting machine 18, shown in diagram, which slits the sheet lengthwise into the number of sections desired, and also cuts the sheets transversely, 5 according to the size of the finished sheet desired.

It will be understood that the drying apparatus extends substantially the full length of the second floor of the building, so that 10 the moisture arising from the paper being dried will rise to the roof and pass out of the ventilators 15, which are arranged at one side of the roof in the present instance and extend the full length of the building. 15 The floor 3, in the present instance, is made in three sections, the central section *a* is directly under the drying mechanism, while the sections *b* are above the section *a* and at each side of the drying mechanism, 20 leaving vertical open spaces 16 between the sections so that fresh air from the first floor will pass up through the open spaces and will pass through the second story to the ventilators 15, as shown by the arrows, 25 Fig. 4, carrying with it any moist air from the drying machine.

In order to keep a blanket of warm air at the ceiling of the second floor, I locate a series of steam pipes 17, as shown in Figs. 30 1 and 4, at the ceiling, so that there is no tendency of the moist air condensing before passing into the ventilators.

The ventilators are preferably made as shown in Fig. 4, part of each ventilator extends 35 down from the ceiling a certain distance and the ventilator extends above the roof, as shown, and is provided with a jacket 18 to prevent cold air cooling the warm air in the ventilator, and any suitable cap 19 is located above the opening.

It will thus be seen that the lower floor, containing the paper making apparatus as well as the finishing and cutting apparatus, is free from the warm air having moisture 45 in suspension, consequently there is no soiling of the paper by dripping water of condensation.

By making the second floor as shown, having the vertical open spaces 16 at each 50 side, the foreman of the plant can stand at any point on the first floor and see the paper passing through the drying apparatus, as the underside of the drums are exposed, and he can also watch the forming apparatus as well as the finished product, as the two mechanisms 5 and 18 are arranged close together. Furthermore, by locating the mechanism on the two floors, a comparatively short main driving shaft 20 55 is required.

Heretofore the making apparatus was at one end of a long building and the finishing calendering rolls and cutter were at the opposite end, while the long drying mechanism was at the center, making it extremely

difficult to watch the progress of the paper through the machine, and this arrangement required the employment of a large number of men.

I have illustrated the machine in diagram, as the detail construction of the several mechanisms composing the machine may be modified without departing from the essential features of the invention. 70

I claim:—

1. A paper-making apparatus having paper-forming and paper-drying mechanisms located at different levels, and a floor separating said mechanisms, said floor having passages extending along the drying- 80 mechanism and connecting with the space above and below the floor and permitting cooling air currents from a lower level to pass into and ascend through the higher level containing the said drying-mechanism 85 and to serve as a carrier of the moist air arising from the latter.

2. A continuous paper-making apparatus comprising the combination of a paper-making mechanism, a paper-drying mechanism, a paper-finishing mechanism, and a floor intervening between the paper-making and paper-drying mechanism, said floor locating the paper-drying mechanism above the paper-making mechanism, and being 95 transversely discontinuous along substantially the length of the drying mechanism to permit fresh air currents from a lower level to ascend through the level containing the drying-mechanism and carry with 100 them the moist air arising from the said drying-mechanism.

3. The combination in a paper-making apparatus, of a building having two floors; paper-making mechanism and calendering 105 rolls and cutters on the lower floor; drying-mechanism extending substantially the full length of the upper floor, the upper floor being made in two levels so as to provide intermediate passages distributed along the 110 drying-mechanism for air to rise from the lower floor to the upper floor; and means for allowing the moist air of the upper floor to escape.

4. A continuous paper-making apparatus 115 having paper-forming mechanism and paper-finishing and cutting mechanism, including calendering rolls on one level; drying-mechanism located on a level above the other two mechanisms; a floor separating 120 said mechanism; means for drawing off the moist air rising from the paper passing through the drying mechanism, the finishing mechanism for the paper terminating at a point where the making mechanism begins, so that an operator can see both the beginning and the finish of the paper. 125

5. The combination in a paper-making apparatus, of paper forming and paper-drying mechanisms located at different 130

- levels; a floor separating said mechanisms, said floor having air passages therein extending along the drying mechanism; and a series of ventilators at the roof of the upper floor in which the paper drying mechanism is located, so as to cause an air current through the passages in the floor to carry off the moist air from the paper passing through the drying mechanism.
- 10 6. The combination in a paper-making apparatus having paper-forming and paper-drying mechanisms located at different levels; a floor separating said mechanisms, said floor having air passages therein extending along the drying mechanism and 15 furnishing a communication between said levels; a series of heating pipes located in the ceiling of the room in which the drying mechanism is located; and a series of ventilators at the ceiling of said room so as to 20 carry off the moist air passing from the drying apparatus.

In witness whereof I affix my signature.
FRANK P. MILLER.
